UNITED STATES PATENT OFFICE

ROY W. HARVEY, OF CHICAGO, ILLINOIS

HIGH AND LOW AUDIOFREQUENCY AMPLIFICATION CONTROL

Application filed May 11, 1928. Serial No. 277,014.

This invention relates to an audio amplification system, and it pertains more particularly to a system adapted to be used selectively with a phonograph or radio to vary tone quality and expression while a record is 5 being played or a radio program is being received.

The object of this invention is to provide a system in which the value of notes of high frequency may be varied, enhanced or suppressed without appreciably affecting the value of the notes of low frequency, and in which the value of the notes of low frequency may be suppressed or accentuated at will without appreciably affecting the value of the 15 notes of high frequency, both of these regulations being separate and distinct from the ordinary volume control. The high register includes notes as produced by violin, flute, clarinet, soprano voice, etc., while the low register includes those produced by the tuba, bass viol, kettle-drums, organ, etc.

A further object of my invention is to provide an amplification system with audio frequency controls to bring out the richness of the deepest bass or the delicate overtones of the highest soprano, or both, to suit the mood of the listener, or to correspond to the intended expression of the composer or artist. 25 (The suppression of the upper register also eliminates needle scratch.)

A further object is to provide an amplifier cabinet with a volume control and with high and low register amplification controls in combination with a speaker located at a distance therefrom whereby the microphonic noises set up by the vibration of the speaker will not affect the tubes or cause electrical disturbances in the amplifier, and whereby a listener seated by the amplifier controls may regulate the expression of the music while the speaker is located at an acoustically correct position in the room.

A further object is to provide an improved 45 electrical circuit for independently varying the amplification of the high register and low register vibrations during the reception thereof.

A further object is to provide a compact arrangement of radio and phonograph pick-up,

an audio amplifier, audio controls, and a power supply therefor.

Other objects will be apparent as the detailed description of my invention proceeds.

My invention may be briefly characterized as a system which makes use of capacity in 55 series with a variable resistance which acts as a variable frequency-cut-off, said cut-off being shunted across the grid circuit of the first amplifier stage for controlling the high register, a similar capacity and variable resistance 60 being connected in series across the audio impedance coupler for controlling the low register, and a variable resistance being shunted across the grid circuit of the second amplifier 65 circuit for volume control.

The outstanding feature of this arrangement is that the tone quality or the relative values of the upper or lower register notes may be regulated while the record is playing. 70 Various speakers are designed to bring out certain frequencies and the better speakers have been designed to respond throughout a very large range, but these speakers are not intended to be changed while music is being played. The present invention may be compared to the stops of an organ, which bring out the richness and fullness of certain frequencies, while suppressing other frequencies. 75

It should be noted that while the high and low register amplification controls are independent of each other and affect different portions of the amplification-frequency curve, the shape of the curve as a whole is dependent on the position of both controls. In other words, 80 it is the shape of the entire amplification-frequency curve that determines the tone quality and amplification characteristics of the sound reproduction, and since each of the controls has a different effect on the shape of 85 this curve, each is dependent on the other and coacts therewith to produce a curve of the desired shape, as will be hereinafter pointed out. 90

In the accompanying drawings which represent a preferred embodiment of my invention, and in which similar parts are designated by like reference characters throughout the several views:

Fig. 1 is a perspective of my improved phonograph amplifier cabinet and speaker 100

unit, part of the amplifier cabinet being broken away to illustrate the tone control;

Fig. 2 is a plan view of the top of the cabinet shown in Fig. 1;

Fig. 3 is a graph illustrating the effect of the high register and low register controls as compared with the volume control;

Fig. 4 is a diagrammatic representation of the entire system, showing the relative arrangement of the pick-up amplifier controls, etc.;

Fig. 5 is a wiring diagram of a combination transformer-coupled impedance-coupled, and push-pull-coupled amplifier circuit provided with my high register, low register and volume controls;

Fig. 6 is a modified volume control; and

Fig. 7 is a modified low register control.

In Fig. 1, I have shown the phonograph and/or radio cabinet 10 provided with a suitable cover 11 and a rotatable turntable 12 with which cooperates the swinging arm 13 carrying the pick-up device 14, the needle of which cooperates with grooves in a record 15 carried by the rotatable table 12. Adjacent the rotatable table I have provided a control panel 16 carrying a switch 17 for controlling the power supply to the amplifier and to the turntable motor, a control 18 for regulating the volume of the reproduced sound generally, a control 19 for suppressing or enhancing the high register notes, and a control 20 for similarly affecting the low register notes. I may also provide suitable receptacles 21 for records and other features which are characteristic of phonographs of this type.

A jack 22 is provided at one end of the cabinet to receive the plug for connecting my amplifier system with a radio receiving set. This jack, of course, could be omitted and the receiving set built into the cabinet without departing from my invention.

In the bottom of the cabinet I provide an opening 23 through which extends a cable 24 carrying the necessary conductors for actuating the speaker 40 which is mounted in a suitable cabinet 25. I prefer to use an electrodynamic speaker of the electromagnet 50 movable coil type, although any suitable speaker may be used which will respond to the necessary frequencies. When it is desired to use a speaker of the fixed magnet type, however, provision must be made in the filter 55 circuit to take the place of impedance 59, which, in my device, serves both as a coil for the electromagnet and as a choke in the filter circuit.

It will be apparent that the operator or listener may sit adjacent the cabinet 10, select any desired records, and vary the tone quality, amplification, or relative value of notes of the upper and/or lower register at will, the speaker being placed at some distance ~~at~~ therefrom according to the acoustics of the

room. The person playing the records can readily change needles and records without the necessity of getting up from the chair, and at the same time he can enjoy the music because the loud speaker is not at his ear but at the end of a thirty-foot cable and placed in the most acoustically perfect position in the room. While this expedient has been used with radio receivers, it is unique with phonographs, and in addition to the feature above stated, it eliminates the effect which the low note vibration of the speaker diaphragm would otherwise have upon the tubes and the electrical characteristics of the amplifier system.

Fig. 3 shows diagrammatically the effect of the three controls, the curves representing on an exaggerated scale the amplification-frequency characteristics of the speaker. The volume control 18 changes the amplification (ordinates) of the conventional curve A(18) without changing the shape of the curve as is shown by the dotted line A'. When the high register control 19 is turned to decrease the resistance 19R, the high frequency register is suppressed, and since the low register remains substantially unaltered, we have an entirely different amplification-frequency curve B(19). When the low frequency control 20 is turned to decrease resistance 20R, the low frequency register is accentuated to give an amplification-frequency curve in which the low register predominates C(20).

From an inspection of this graph (Fig. 3), it will be evident that elevating the low frequency portion of the curve is not, as would be expected, equivalent to lowering the high frequency part of the curve, because the resultant curve shape or speaker-amplifier characteristic is entirely different in these two cases. Controls 19 and 20 cooperate to determine the curve shape while control 18 changes the ordinates of this curve without affecting its shape.

Referring to Fig. 4, the pick-up 14 is connected by suitable conductors 26 to a jack 27 adapted to receive a plug whereby flexible members 28 are disconnected therefrom when connected to a radio receiving set. In either case the signal from the pick-up or radio receiver is transmitted through conductors 29 to a plug 30 which also carries the conductors leading to the control dials. Thus the conductors 31 and 32 lead to the volume control 18, conductors 33 and 34 to the high register control 19 and conductors 35 and 36 to the low register control 20. (See Figs. 4 and 5.) All of these conductors lead to the single plug 30 which is provided with the necessary number of contacts, and which may be inserted in a suitable socket 30S in much the same manner that a radio tube is inserted in its socket.

A second plug 37 carries the wires 38 and 39, which are enclosed in cable 24 extending through the hole 23 in the bottom of the cabi-

net 10 and which lead to the speaker cabinet 25. Wires 38 are connected to the electromagnet coil of the speaker and wires 39 to the movable coil thereof, as will be apparent from Fig. 5. By having plugs 30 and 37 removable and by providing other suitable sockets, the amplifier unit may be removed bodily from the rest of the system when it is necessary to repair or to improve the circuit.

Power for my amplifier system is supplied from the ordinary alternating current electric lighting source, connection being made by conventional plug 41. A conductor 42 leads from this socket to a terminal of switch 17. A conductor 43 leads from the other terminal of switch 17 to a terminal of socket 44, the other terminal of which is connected by conductor 45 to plug 41. A conductor 46 leads from conductor 43 to a pilot light 47, connected in series with record compartment lamp 48, which in turn is connected by conductor 49 to conductor 45. It will be obvious that the record compartment and pilot lights 25 will be turned on when switch 17 is actuated and that they will indicate the fact that the system is connected to the power source.

A plug 50 cooperates with socket 44 and is connected by conductors 51 to a fuse block 52. The fuse block serves as a protection to limit both the current to the amplifier through conductors 53 and the current to the motor through conductors 54, socket 55 and plug 56. The motor 57 may be of any suitable type 35 and is controlled by switch 17', as is shown in Fig. 4.

The wiring diagram of the amplifier system is shown in Fig. 5, this circuit being mounted as a unit in the system and being removable therefrom as above described.

The conductors 53 (see Fig. 4) are connected to the primary of transformer 58 (see Fig. 5), which supplies the necessary power for operating audio amplifier tubes I and II, 45 push-pull amplifiers III and IV, and rectifier tube V.

The amplifying circuit per se forms no part of my present invention and will not be described in detail. It should be noted, however, that the electromagnet coil 59 of the speaker also serves as a choke in the filter circuit 60. Resistance 62 limits the voltage in the plate circuits of stages I and II. Negative bias is provided by means of a suitable 55 resistance 61. Impedances 59 and 62 cooperate with the various condensers to eliminate ripple, etc., as is well known in the art.

The volume control is preferably a variable resistance 18R of about 200,000 ohms, 60 which is connected between the grid of the second audio amplifier tube II and the negative side of the circuit by conductors 32 and 31, respectively. This, in effect, by-passes the energy and is commonly known as a "loss 65 method". It may be applied across the grid

circuits in either the first or second stages or across the pick-up, and its position in the second stage is shown in Fig. 5. An increase in the resistance 18R increases the energy supplied to the grid, and therefore increases the amplification of all frequencies, i. e., increases the volume (see Fig. 3).

Other methods may be used to vary the volume, such as, for instance, the potentiometer method illustrated in Fig. 6, wherein the pick-up circuit is connected to a resistance 61 and a drop is taken from any portion of this resistance and fed into the input of the amplifier by means of conductor 62.

The high register control preferably comprises a condenser 33C of about .03 microfarads connected in series with a variable resistance 19R of 200,000 ohms, said elements being connected from the grid of the first amplifier to the negative side of the circuit. In this arrangement a variation of the resistance varies the effective capacity shunt, thereby varying the frequency cut-off in accordance with the formula:

$$X_c = \frac{1}{2\pi f C}$$

X_c = impedance of the coupling

f = frequency of the signal

C = capacity of the coupling

Condenser 33C will by-pass high frequencies much more readily than low frequencies, and by rendering the condenser shunt more or less effective by means of the variable resistance, the high frequency signals may be shunted out to any desired extent. It is understood, of course, that this arrangement might be connected across the pick-up circuit or across the grid circuit of the second tube. In any case, an increase in resistance 19R increases the amplification or volume of high register notes.

The low register control comprises a condenser 35C of about .03 microfarads in series with a variable resistance 20R of 200,000 ohms, these elements being connected in series across the audio impedance coupling 64. The choke coils 65 do not form an inductive coupling but act as an impedance coupler between the plate circuit of the first amplifier and the grid circuit of the second amplifier. The fixed resistance 63 prevents oscillation when the resistance 20R is cut out.

It will be evident that a variation in resistance 20R will vary the oscillation constant and will have a damping effect on the two impedance circuits into which it is connected, thus suppressing the low frequency signals transmitted from one stage to the next without materially affecting the high frequency signals. An increase in resistance 20R decreases the amplification or volume of low register notes.

In Fig. 7, I have shown a modification of

this control where resistance 66R is connected in the grid circuit of the second stage.

It will therefore be apparent that my three controls have separate and distinct functions

5 and that each cooperates with and is dependent upon the other for varying both the shape and the ordinates of the amplification-frequency curve representing speaker-amplifier characteristics, as shown in Fig. 3.

10 While I have specifically described a preferred embodiment of my invention, it is understood that I am not limited to the details set forth therein except as defined by the following claims.

15 I claim:

1. In an audio frequency amplifier system, means for controlling the amplification of the volume throughout the entire frequency range, means for varying the amplification 20 of low frequency without appreciably affecting the high frequencies and means for varying the amplification of high frequencies without appreciably affecting low frequencies.

25 2. In an amplifier system of the type wherein two stages are connected in cascade by impedance coupling, means for controlling amplification of the entire frequency band, a variable resistance and a condenser 30 connected in series across the impedance coupling for varying the low register, and a variable resistance and a condenser connected in series across a grid circuit for varying the high register.

35 3. In an amplifier system of the type wherein two stages are connected in cascade by impedance coupling, means for varying the high frequency signals without materially affecting low frequency signals, and

40 means including a variable resistance connected between the plate of the first stage and the grid of the second stage whereby the low frequency signals are limited without materially affecting the high frequency signals.

45 4. In an audio amplifier system including two stages of amplification connected in cascade by impedance coupling, a variable resistance in series with a capacity connected 50 from the grid of the first stage to ground and a variable resistance and a condenser connected in series across the impedance coupling.

5. In combination, a plurality of amplifier tubes, connections associated with said tubes to complete a single amplifier system, each tube being connected to amplify both 55 high and low frequency signals, said connections including means for varying the 60 amplification of high frequency signals in said amplifier system without appreciably affecting the amplification of low frequency signals, means for varying the amplification of low frequency signals without appreciably 65 affecting the amplification of the high fre-

quency signals, and independent controls for actuating said means, whereby the tone characteristics may be varied while the signal is being amplified.

6. In an amplifier system comprising a plurality of tubes connected to amplify both high and low frequencies, and adapted to give a characteristic speaker-amplifier curve shape, means for varying the degree of amplification throughout the entire wave length 70 band whereby the position of the curve is varied without appreciably affecting its shape, and independent means for varying the high or low frequencies whereby the curve shape may be varied without appreciably affecting the position of the curve. 75

7. In an amplifier system having a plurality of stages, means for varying the low frequency signals without materially affecting the high frequency signals, and means including a variable resistance connected in series with a condenser across the grid circuit of the first stage whereby the high frequency signals are limited without materially affecting the low frequency signals. 80

8. In an amplifier system of the type where two stages are connected in cascade by impedance coupling, means for varying the high frequency signals without materially affecting the low frequency signals, means including a variable resistance connected between the plate of the first stage and the grid of the second stage whereby the low frequencies are limited without materially affecting the high frequency signals, and independent controls for actuating each of said means, said controls being accessible for operation while sound is being amplified whereby tone qualities and characteristics may be continuously modified. 90

9. In an amplifier adapted to give a characteristic speaker-amplifier curve shape, means for varying the degree of amplification of the entire wave length band whereby the position of the curve is varied without appreciably affecting the curve shape, independent means for varying the high or low frequencies whereby the curve shape may be varied without appreciably affecting the position of the curve, and controls associated with each of said means whereby the tone qualities and characteristics may be continuously changed while sound is being reproduced. 105

110 In witness whereof, I hereunto subscribe my name this 9th day of May, 1928. 120

ROY W. HARVEY.
